UNITED STATES PATENT OFFICE.

JOSEPH MULLIGAN, OF SHEFFIELD, ENGLAND.

DESIGN FOR A VENTILATOR.

SPECIFICATION forming part of Design No. 23,029, dated January 30, 1894.

Application filed November 18, 1893. Serial No. 491,354. Term of patent 14 years.

To all whom it may concern:

Be it known that I, JOSEPH MULLIGAN, a subject of the Queen of Great Britain, and a resident of Sheffield, county of York, England, 5 have invented and produced a new and original Design for a Ventilator, of which the following is a specification, reference being had to the accompanying drawings, showing the said extractor.

10 Figure 1 is an elevation view of the ventilator showing my design. Fig. 2 is a sectional elevation view taken on a plane perpendicular to Fig. 1.

15 The leading feature of my design consists in a circular shaft surmounted by two cones

placed with their bases some distance apart, and the narrow ring encircling the cones and meeting the sides of the shaft as shown.

C is the shaft circular in form.

A A are the cones, and B the ring.

20

Encircling the bases of the cones are projecting flanges E, E.

What I claim is—

The design for a ventilator as herein shown and described.

JOSEPH MULLIGAN.
